UNITED STATES PATENT OFFICE

WILLIAM D. HAMERSTADT, OF INDIANAPOLIS, INDIANA, ASSIGNOR TO ROCKWOOD MANUFACTURING COMPANY, OF INDIANAPOLIS, INDIANA, A CORPORATION

DUST GUARD

Application filed October 3, 1927. Serial No. 223,564.

This invention relates to an improved dust guard for axle journal boxes.

The chief object of this invention is to improve the construction of dust guards of the general character such as disclosed in prior Patent No. 1,574,968, granted March 2, 1926.

The chief feature of the invention consists in the construction of the dust guard such that it has a certain inherent resiliency coupled with relatively great strength reducing breakage in mounting to the minimum and which, when mounted, is multiple sealing in character and which is self-draining and cleaning.

The full nature of the invention will be understood from the accompanying drawings and the following description and claim:

In the drawings Fig. 1 is an elevational view of a truck axle wheel journal and box, the journal, box and dust guard being shown in section to illustrate the mounting of the invention. Fig. 2 is an enlarged perspective view of the dust guard. Fig. 3 is an enlarged transverse sectional view of the same.

In the drawings is illustrated a conventional form of axle, wheel, journal and box. 10 indicates the axle, 11 the wheel, 12 the connecting portion between the wheel-supported portion and the journal-supported portion of the axle. The frame work of the truck carries the housing 14 having the closure 16, and said housing 14 includes the axle-receiving opening 17 which is defined by a groove or pocket 18 having mouth 19. All of the foregoing is old in the art and is the standard railway truck construction.

Dust guards have been mounted in the groove or pocket 18 being positioned therein thru the mouth 19 prior to the forcing of the axle into the housing. Since the relative parts are such, the dust guards must wear rather than the associated wheel and supporting parts and the function of the dust guard is to prevent the entrance of dust and dirt, picked up by the wheel and the air currents caused by the train passing over the right-of-way, from entering the journal box and thereby increasing the friction between the journal and the journal end of the shaft which

would cause a hot box and burn out the bearing.

The improved dust guard consists of a pair of spaced fibre sheets 20 and each is composed of material commonly known as fibre board such as that suitable for fibre pulley purposes. Each includes a circular opening 21 and the punching therefrom, which is waste, is suitable for the manufacture of fibre or paper pulleys. Each plate 20 is a composite homogeneous member having a U-shaped exterior outline having a circular opening 21, the center of which is not coincident with the center of the curved portion of the U-shaped outline. The stock is relatively thin and is approximately one-sixteenth to one-quarter inch in thickness with the usual limit of about one-eighth inch or less. This permits the material to be punched instead of cut, for forming the opening 21. A punched opening leaves a free, clean hole and also leaves a relatively clean periphery on the blank, which, as previously stated, can be used in the manufacture of fibre pulleys.

The pocket 18 is normally three-quarters of an inch in width to receive a five-eighths inch dust guard, these requirements being standard and required by the Master Car Builders Association. Interposed between the two parallel plates 20 is a transverse spacing strip 22. Along the upper edge and extending along each parallel side of the U-shaped dust guard are the longitudinal spacing strips 23. The result therefore is a pocket 24 positioned above the upper half of the opening 21 with an outlet or mouth 122 therebeneath and the side wall passages 25 (see Fig. 2).

The advantages of the present construction are that, when the axle is inserted in the axle-receiving opening of the journal box, there is a slight resiliency in the material and the same does not crack should the axle be slightly askew. Furthermore, the longitudinal spacing strips 23, in addition to forming one wall of the channel, reinforces the dust guard at its weakest point which is at the opposite portions approximately determined by the projected diameters positioned perpendicularly to the longitudinal spacers 23. Thus breakage is reduced to a minimum as the fibrous

material will not shatter or fracture as is the case with wooden dust guards and will not break at the mid section by reason of the reinforcement provided.

5 In addition to the foregoing advantages, the resultant construction of the dust guard incures a double seal,—that is, each plate 20 constitutes a single dust guard with the spacing strip 22 and the side strips 23, and would 10 be sufficient for a normal operation and, therefore, both plates insure multiple sealing.

In addition to the foregoing multiple sealing action, such dust and dirt that passes thru the opening 21 of the first plate 20 or that 15 positioned next to the wheel will, if carried around on the axle, be thrown therefrom into the chamber 24 and thence out thru the mouth 22 to the bottom of the pocket 18. Water and the like also which might work along the axle 20 12 will be trapped in the bottom of pocket 18 by the aforesaid construction and there thereby results a self-cleaning and self-draining chambered dust guard for having the advantages of a multiple seal and longer life, less 25 breakage in mounting and, in addition, having a cost of manufacture not exceeding that of a standard wooden dust guard. The multiple plate dust guard also is reversible.

The invention claimed is:

30 An open ended dust guard for truck axle journals and of somewhat rectangular outline but having one side of curved outline, comprising a pair of relatively thin fibrous plates each having a circular opening substantially 35 registering with the other and of the outline designated, and a plurality of spacing and reinforcing members extending along all of the straight sides of and between said members forming a chamber of materially greater 40 cross sectional area than the area of the circular opening as well as coextensive with said registering circular openings and forming a single discharge duct between the plates and at the curved edges thereof, said discharge duct throughout its length being at 45 least as wide as said opening.

In witness whereof, I have hereunto affixed my signature.

50 WILLIAM D. HAMERSTADT.
